(57) **CLAIM**

The ornamental design for a reinforced external turret for electrical equipment, as shown and described.

DESCRIPTION

FIG. 1 is a rear view of a reinforced external turret for electrical equipment showing our new design;

FIG. 2 is a front view thereof;

FIG. 3 is a left view thereof;

FIG. 4 is a top view thereof;

FIG. 5 is an oblique view thereof;

FIG. 6 is a right side view thereof; and,

FIG. 7 is a bottom view thereof.

The broken lines and the portions within illustrate portions of the article that form no part of the claimed design.

1 Claim, 7 Drawing Sheets
